(57) **CLAIM**

The ornamental design for a bottle flange, as shown and described.

DESCRIPTION

FIG. 1 is an elevational view of the neck portion of a bottle flange in accordance with the present invention;

FIG. 2 is an enlarged top perspective view of the bottle flange illustrated in FIG. 1;

FIG. 3 is a top plan view of the bottle flange illustrated in FIG. 2;

FIG. 4 is a side view of the bottle flange illustrated in FIG. 2; and,

FIG. 5 is a bottom plan view of the bottle flange illustrated in FIG. 2.

The broken line showing is for illustrative purposes only, and forms no part of the claimed design.
